UNITED STATES PATENT OFFICE

EUGENE W. SCHELLENTRAGER, OF SHAKER HEIGHTS VILLAGE, OHIO, ASSIGNOR TO THE ATLAS BOLT & SCREW COMPANY, OF CLEVELAND, OHIO, A CORPORATION OF OHIO

BIN-GATE-OPERATING CYLINDER

Original application filed December 7, 1925, Serial No. 73,723. Divided and this application filed June 15, 1927. Serial No. 198,985.

This invention relates to apparatus for handling and conveying granular materials, such as ore and other ingredients which enter into charges for blast furnaces, or the like.

5 This apparatus usually includes suitable stationary bins for the various ingredients arranged along the side of a conveyor such as a car or other vehicle provided with a suitable container for receiving the various materials and also provided with a bin gate handling mechanism adapted to manipulate and control the opening and closing of the bin gates when the conveyor is in place in front of one of the bins. In these arrangements heretofore constructed, there is danger of the operator of the car, or vehicle, moving from one bin to the other while the bin gates are open resulting in damage to the bin gate and a loss of materials. The specific mechanism on the conveyor or car for handling the bin gates has also been of a character such that it was expensive to manufacture and could not be produced at a suitable figure which would interest the user. Another difficulty arising from the constructions heretofore employed resided in the fact that no means was provided for limiting the downward movement of the piston, where such devices were used, to prevent the shock incident 15 to the lowering of the gate in place and resulting in great damage to the apparatus.

This invention contemplates a structure employed for the bin gate handling mechanism whereby it is efficient in operation and 20 simple in construction and lends itself readily to production at a reasonable cost, and is a division of my copending application bearing Serial No. 73,723, filed Dec. 7, 1925, patented October 15, 1929 as Patent 1,731,271.

40 In the arrangement shown in the drawings, Fig. 1 is a view showing an installation; Fig. 2 is an enlarged detail view of the door handling mechanism; Fig. 3 is a vertical sectional view on line 3—3 of Fig. 2; Fig. 4 is 45 a section upon the line 4—4 of Fig. 2; and Fig. 5 is a detail view of the bleed check valve.

In the embodiment shown in the drawings, the ore or other material chute comprises the 50 walls 1 and 2 supporting an intervening hop-

per bottom 3 and providing a discharge throat 4 through which the material is discharged against an inclined chute member 5 projecting outward to a point above the container 6 which is supported upon a suitable frame 7 mounted on wheels 8 operating upon tracks 9 arranged between the two walls 1 and 2. The axle 10 carrying the wheels 8 is driven by a motor of any suitable type, not shown. There are a plurality of these bins 55 containing the various materials used in a charge for a furnace for example, and each bin is controlled by a bin door or gate, and each gate comprises a swinging member 11 for checking the main discharge from the 60 chute and an auxiliary gate 12 for checking the final limited discharge, this gate structure being one which is familiar to those skilled in the art. The auxiliary gate 12 is provided with outwardly extending side 65 members 13 which receive a cross bar 14 by means of which the auxiliary gate and main gate are raised by suitable bin gate handling mechanism. Secured to the car or conveyor frame 7 is a suitable framework 15 for supporting the platform 16 for the operator and the bin gate handling mechanism about to be described. The car is also provided with a suitable trolley member generally indicated 70 at 17 and adapted to engage the circuit rails 75 18 as shown in Fig. 1.

The bin gate operating mechanism comprises upper and lower brackets 19 and 20 in the form of a split ring structure adapted to be clamped by the bolts 21 about the tubular cylinder 22. This tubular cylinder is of tubing adapted at its lower end to seat at the shoulder seat 23 on the lower cylinder head 24. This cylinder head is provided with opposed ears 25 which receive through bolts 26 90 extending upwardly in parallelism with the cylinder and through corresponding ears 27 projecting diametrically from the upper cylinder head 28. Suitable nuts 29 and 30 on these bolts serve to clamp the two cylinder heads upon the ends of the cylinder. The upper cylinder head is provided with a stuffing box structure indicated at 31 and furnishes a packing means for a piston rod 32 which extends into the cylinder and is there 95 100

provided with a piston having a metallic packing ring 33 in a suitable groove therein. The piston rod 32 at its upper end is reduced at 34 where it passes through a cross head 35 held on the reduced portion by a suitable nut 36. Each outer end of this cross rod is provided with a reduced portion 37 for passage through a suitable opening in the upper end of a side link or bar 38 and held thereon by a suitable cotter pin 39. Each link or bar extends downwardly and is secured to a sleeve guide or slide 40 of a bin gate engaging member, to be described, by suitable bolts or screws 41, the two links lying in the same diametrical plane with the bolt 26 and passing through the cylinder axis. The bin gate engaging member comprises the two sleeve guides 40 and a connecting yoke part 42 extending around one side 20 of the cylinder, as shown in Fig. 4. This yoke portion is provided with an outwardly extending lifting lug or foot 43 adapted to project outwardly normally to said plane to a point where it may engage freely under the 25 cross bar 14 of the auxiliary bin gate.

It is obvious that when pressure is applied below the piston it will rise in the cylinder and lift the bin gate member and raise the gate, and when lowered will return the gate 30 to closed position.

The supply for motor fluid for the cylinder and piston structure thus far described is made up of a supply line or pipe 44 connected to any suitable source of fluid pressure and to an engineer valve 45 or any other suitable control common in the art. This 35 valve is connected by a pipe 46 which leads to the upper cylinder head and communicates with the upper end of the cylinder. Another port of this valve is connected by means of a pipe 47 with a T 48, the side opening of which leads through a pipe 49 to a port 50, Fig. 3, in the side wall of the cylinder at a distance from but near the bottom. This 40 pipe 49 is provided with a check valve 51 which opens freely with the exhaust from the bottom of the cylinder and in the direction indicated by the arrow in Fig. 2. The remaining through connection of the T 48 is 45 connected by a pipe 52 through a check valve, of special construction, to the bottom of the cylinder through the connection 54, as shown in Fig. 3. The check valve 53 is similar in all respects to the well known check valve 55 except that its valve member 55 is provided with a small bleed opening 56 leading from one side of the valve to the other. This valve, as shown in Fig. 5 opens toward the cylinder. In other words, the fluid pressure will raise 50 the valve freely and pass to the cylinder to raise the piston in the cylinder; upon the downward movement of the piston, this check valve blocks the free passage at this point and permits only a slow passage of the fluid 55 pressure through the bleed opening 56. The

exhaust from the upper and lower ends of the cylinder are handled by the valve 45 in a well known manner and are delivered to the exhaust pipe 57.

In using the door handling mechanism, the operator shifts the valve mechanism to a position to deliver the fluid pressure to the pipe 47 with the result that it cannot pass the check valve 51 and will be required to pass down and raise the check valve 55 before it reaches the cylinder under the piston. It will perform this operation very readily and will raise the piston in the cylinder to the proper height to fully open the bin gate with which it is cooperating. To close the 70 gate, the operator connects the pipe, or the port in the valve connected to the pipe 47, with the exhaust resulting in the weight of the bin gate causing the piston and the parts connected to it to move downward. The 75 downward movement is very rapid until the piston passes the port 50 when the exhaust is restricted by the small capacity of the bleed 56 in the check valve 53. This small bleed produces such a retarding and cushioning action upon the piston that it is seated 80 very slowly. The ideal arrangement is one where the cushioning effect takes place immediately following the seating or closing of the pin. In cold weather when the oil 85 or other material in the cylinder and piston structure is heavy, it may be necessary to speed up the downward movement of the piston, in which case the operator, by the use of the valve 45, can very readily supply 90 air to the upper side of the piston.

The special form of check with its bleed used to retard the downward movement of the piston very effectively protects the mechanism against damage which might otherwise result from the unrestricted downward movement of the parts on the closing operation.

The construction and arrangement of the parts of this bin gate handling mechanism is such that the entire apparatus may be manufactured and sold at a reasonable cost and when installed is extremely effective in the hands of the average operators.

Another advantageous feature of the foregoing construction of door handling mechanism resides in the arrangement of the smooth tubular cylinder in the supporting clamps, in that these clamps may be loosened and the cylinder adjusted vertically to bring the lifting lug 47 in a critical position with respect to the bin gate cross bar 14. Heretofore, this has been extremely difficult and required considerable dismantling and manipulation of the parts of the mechanism.

What I claim is:

Apparatus of the class described, comprising a cylinder, heads on the ends of said cylinder, through bolts extending from head to head and securing the heads to said cylin-

der, a piston movable in said cylinder, a piston rod movable therewith and extending through one of said heads, a cross head on said piston rod extending laterally thereto in opposite directions in a plane through said bolts, a bin gate operating member slideable on said through bolts and having a foot portion extending outwardly from said cylinder normally to said plane, and bars connecting 10 said cross head and said member, said bars lying in said plane outwardly beyond and adjacent and parallel to said bolts.

In testimony whereof I hereby affix my signature.

15 EUGENE W. SCHELLENTRAGER.
